Primary Examiner — Michelle E. Wilson*Assistant Examiner* — Ciese Moore, Jr.*(74) Attorney, Agent, or Firm* — HYIP; Jie Yang(57) **CLAIM**

The ornamental design for a camping sleeping bag, as shown and described.

DESCRIPTION

FIG. 1 is a first perspective view of a camping sleeping bag showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the camping sleeping bag thereof; and,

FIG. 10 is an enlarged view of the selected portion in FIG. 8.

The broken lines shown in the drawings depict portions of the camping sleeping bag in which the design is embodied that form no part of the claimed design.

1 Claim, 10 Drawing Sheets(56)
